UNITED STATES PATENT OFFICE

ARTHUR J. MOULTON, OF ISLIP, NEW YORK

THEATER

Application filed May 4, 1929, Serial No. 360,516, and in France October 31, 1928.

My invention relates to theatrical appliances and more particularly has reference to theaters having a circular revoluble auditorium surrounded by a stationary annular stage.

The conventional theater construction, wherein changes of scenery and setting on the stage are accomplished by the echelonment in depth of a series of side-sliding panels disposed behind a main drop curtain, is attended with certain obvious disadvantages, among the more important of which may be mentioned the following.

Since essentially the same stage area is used for all scenes and settings, a change of scene can only be accomplished by dropping the main curtain, cutting off the view of the audience from the stage, and then shifting the scenery by side-sliding panels and physically moving the various articles constituting the setting on the stage. This is not only a laborious and fragile process, but what is more serious, it is time-consuming and necessitates an intermission in the action of the play every time a change of scene occurs. Such lengthy intermissions, accompanied by the unavoidable noise on the stage, due to changing the scenery and settings, not only interrupt the continuity of the play but greatly mars the enjoyment of the audience by tedious periods of inaction.

Also, in the conventional type of theater, wherein the auditorium and stage are completely enclosed in a single building, adequate ventilation and fresh air are serious and unsolved problems, especially during hot weather.

Another serious defect of the conventional type of theater is the enormously high ceiling over the stage for the accommodation of drop curtains, a form which is contrary to the laws of acoustics.

It was to overcome these disadvantages existing in the prior art, and to achieve other objects which will be apparent to those skilled in the art, that I have conceived this invention.

An object of my invention is to construct a theater wherein a series of scenes and settings may be presented to the audience with-

out the necessity of changing scenery and setting during the performance.

Another object of my invention is to provide a theater noiseless in its operation so that a change of scene can be accomplished quickly and quietly without any of the usual stage noises occasioned by shifting scenery and settings.

A further object of my invention is to provide a theater in which a panoramic scene may be produced without the impractical method of moving the scenes and settings of the stage before the eyes of the spectators.

Still another object of my invention is to provide a theater wherein adequate ventilation of the auditorium may be obtained during entr'actes.

Yet another object of my invention is to provide a theater of the best possible stage acoustic properties.

A still further object of my invention is to provide a theater so arranged as to present natural out-of-door scenes under the open sky from the same auditorium used for the panoramic stage.

With these and other objects in view which may be incident to my improvements, the invention consists in the parts and combinations to be hereinafter set forth and claimed, with the understanding that the several necessary elements comprising my invention may be varied in construction, proportions and arrangement, without departing from the spirit and scope of the appended claims.

My invention contemplates broadly a theater in which a circular auditorium is surrounded through the major portion of its circumference by a covered stage, with the remaining portion left open to the sky, thereby constituting natural scenery for open air performances.

This circular auditorium is constructed upon a flat-bottomed structure of approximately the same diameter, and floating in water, or other liquid, contained in a suitable reservoir.

This auditorium is maintained at a constant level in relation to the surrounding stage by means of automatic valves, contained within a large vertical tube situated in the

axis of rotation. These valves are operated by the up and down motion of the auditorium, caused by the varying weight of the spectators, allowing water to run in or out 5 of the surrounding reservoir or the float itself in direct proportion thereto. This float is made to rotate about its central axis, by means of water reaction against the walls of the reservoir or by some other suitable mechanical means, thereby bringing the spectators opposite any desired portion of the in-door and out-door stages, the latter being also used during the entr'actes to ventilate the auditorium.

10 15 A circular curtain is hung from the periphery of a ceiling over the auditorium, the diameter of which is approximately equal thereto, and falls to the stage floor throughout its entire circumference, forming the walls of said auditorium. This curtain is split from the ceiling to the floor, and each half can be withdrawn to any desired amount until the two halves are made to occupy a zone back of the spectators of approximately 20 25 one third of its entire circular length, thus giving an uninterrupted view of the entire in-door stage.

The rails from which the curtain is suspended can be rotated by suitable means in 30 a manner and at a speed coinciding with that of the auditorium, thereby keeping the above mentioned split, which forms the opening to the stage, always opposite the spectators.

35 The ceiling over the stage and that over the auditorium form, when the curtain is withdrawn, an uninterrupted surface of practically parabolic form in conformity with the laws of acoustics. This shape also lends itself to the projection of uninterrupted 40 sky effects over both stage and auditorium.

In order to make my invention more clearly understood, I have shown in the accompanying drawings means for carrying the same into practical effect, without limiting 45 the improvements in their useful application to the particular constructions, which, for the purpose of explanation, have been made the subject of illustration.

50 In the drawings:

Figure 1 is a longitudinal vertical section of my improved theater.

Figure 2 is a horizontal section along the line 2—2 of Figure 1, looking in the direction of the arrows.

55 Figure 3 is a fragmentary section along the line 3—3 of Figure 1, looking in the direction of the arrows.

Figure 4 is a fragmentary vertical section of a portion of the ceiling and roof to show 60 certain details of the curtain suspension construction.

Figure 5 is a fragmentary section along the line 5—5 of Figure 4.

65 Figure 6 is a fragmentary horizontal section along the line 6—6 of Figure 4.

Figure 7 is a fragmentary vertical section along the line 7—7 of Figure 4.

Referring to the drawings, in which like elements are denoted by the same reference numerals throughout, and more particularly 70 to Figures 1 and 2, my improved theater consists of a central revolvable circular auditorium 1, surrounded by a stationary annular stage 2. The auditorium 1 is provided with a floor 3 having a series of arcuate rows 75 of seats 4, arranged as shown in Figure 2 and echeloned in elevation as indicated in Figure 1.

It will be appreciated that while, for simplicity I have shown only one floor, 3, for 80 seats, additional balconies and galleries could readily be added above this floor, as in conventional theaters. In front of the seats 4 are the usual orchestra pit 5 and proscenium 6. Beneath the floor 3 are a plurality of staircases 7 and 8 leading to a plurality of entrances or exits 9 and 10 which communicate with the passageways 11 and 12 leading to the exterior of the building.

Below the ground floor 13 are two lower 90 floors 14 and 15 which are subdivided into a number of rooms which may be used as smoking rooms, toilets, a clinic, a printing room, a press room and other auxiliaries of a theater. Below the ground floor 13, the 95 entire auditorium is constructed as a cylindrical water-tight unit with impervious walls 16 and integral bottom 17. Surrounding the auditorium below the ground level is a large 100 water-tight tank or pool 18 in which is constantly maintained a sufficient level of water to float the whole auditorium 1. On the bottom floor 17 of the auditorium there are installed a plurality of electric motors 19 geared to water propellers 20, which are adapted to 105 rotate in the water in pool 18 and by their reaction revolve the auditorium about its central vertical axis. In order to render the impulse of the propellers 20 more effective, pool 18 is provided with a series of radial 110 baffles 21 attached to its outer wall and extending inwardly to a close proximity to propellers 20.

In order to maintain the floor 13 and proscenium 6 at the exact levels of the ground 115 and stage respectively under different loads on the auditorium, a central control station 22 is provided in the basement of the auditorium. This connects through conduit 23 with pumps and valves (not shown) which 120 supply more or less water to tank 18 through pipe 24 upon operation of control valve 25. It is obvious that when more water is pumped into tank 18, a greater buoyant effect is exerted upon the auditorium 1 and it will tend 125 to rise with reference to the ground and stage levels, and the opposite effect secured by withdrawing water from tank 18.

By a proper manipulation of control valve 130 25, auditorium 1 can be made to maintain its

level with the ground and stage for any allowable load. By making the outer walls of auditorium 1 smooth, and bringing them within close working proximity to the encircling 5 walls of the stage, any tendency of the floating auditorium to tilt or cant by eccentric loading is prevented by the restraining action of the encircling stage walls. Suitable spacing rollers may be inserted between the outer 10 surface of auditorium and the encircling stage walls to properly center the floating structures, and prevent scraping when in motion.

The stage 2 is enclosed for approximately 15 three-fourths of its circumference by an encircling back wall 26 and wing walls 27. Behind wall 26 are constructed a series of dressing rooms, vestibules and other stage auxiliaries on a plurality of floors, denoted 20 generally by the reference numeral 28, which communicate with stage 2 by a plurality of doors. The remaining quarter section of the stage 2 consists of an open air or outdoor stage 29 arranged as a garden or other suitable landscape, and supported at stage level 25 by a masonry floor 30.

From the foregoing description it is obvious that by rotating the auditorium 1 the spectators may be brought opposite the open air section to view open air performances amid natural scenery. This also permits ventilation of the theater between the regular 30 acts on the indoor stage.

The indoor stage 2 is covered with an 35 acoustic false ceiling 31 of parabolic vertical section, which merges with a rotatable acoustic ceiling 32 above the auditorium so as to present an uninterrupted surface of substantially parabolic configuration in conformity 40 with the laws of acoustics. This shape of ceiling also lends itself to the projection of uninterrupted sky effects over both stage and auditorium.

Rotatable acoustic ceiling 32 is circular in 45 plan and is supported just below the permanent ceiling 33 of the theater by a series of rollers 34 attached to an annular flange 35 integral with ceiling 32, which rollers travel on a track 36 mounted upon an annular curtain wall 37 integral with roof 38 of the theater. (See Figure 4.) In order to center the 50 rotation of ceiling 32 about the vertical axis of the auditorium, a series of auxiliary rollers 39 are attached to flange 35 and bear upon the track 40 attached to the suspension wall of ceiling 33.

Between the auditorium 1 and the stages 2 and 29 is suspended from revolvable ceiling 32 a two-piece circular curtain 41 which is 55 adapted to completely surround the auditorium 1, and thus cut off from the spectators therein any view of the indoor stage 2, or outdoor stage 29. Curtain 41 is made of any suitable textile material and may even be 60 made of asbestos fabric, not too stiff to drop in

folds when drawn back. Curtain 41 is supported at short intervals along the entire periphery of its upper edge by links 42 attached to stirrups 43 mounted upon rollers 44 which roll along a track 45 fastened to ceiling 32 65 by a series of brackets 46.

Rollers 44 are maintained equispaced from each other by a continuous pair of toggle arms 47 which are pivotally attached to each stirrup 43 and to a central fixed bracket 48 riveted to track 45 at a point diametrically opposite to the center of proscenium 6. A portion of the stirrups 43 carry opposite toggle arms 47, a bracket to which is fastened a plurality of continuous pull ropes 49 which are 70 carried on a series of rollers 49' around the outer periphery of ceiling 32 and through a central channel 50 thereof. Pull ropes 49 at some convenient concealed point in ceiling 32 are connected to an operating remote control mechanism (not shown) so that curtain 41 may be manipulated from an operating station at the back of the stage.

The rotatable ceiling is operated by electric 75 motors (not shown) the speed of which are governed automatically by the speed of the auditorium so as to maintain at all times the same relation between these two components.

However, instead of rotating the ceiling 80 32 by means of motors, as just described, a construction such as that employed in Figures 4 and 5 may be used. By such a construction there is attached to the fixed bracket 48 on the ceiling and outside of the curtain 41, a bracket or rod 51, whose lower end is secured 85 to the wall of the rotatable auditorium 1 in any convenient manner. Hence, rotation of the auditorium is transmitted to the ceiling 32 and causes the ceiling and curtain to rotate at the same time and speed.

As the ceiling, curtain and auditorium revolve always at the same time and speed thereby giving the spectators the illusion that they remain stationary while the stage 2 passes before them.

There is no frame defining the opening of the curtain in front, and consequently nothing limits the separation of the two halves of the curtain except the construction of toggle arms 90 47, which are designed to permit an opening of the curtain of at least 240°.

Since the curtain 41, which may be made heavy and thick, extends from the floor of the stage 2 to ceiling 32 and moves as a unit with the latter, it forms, so to speak, the 95 walls of the auditorium and it absorbs all the sound waves which strike it and prevents any echo effects. This construction, together with my novel parabolic sound reflecting ceiling 31, gives to my theater very superior 100 acoustic properties.

From the foregoing description it is clear 105 that I have provided a theater wherein the auditorium accommodating the audience or spectators is adapted to be turned about the 110

center of an annular stage extending over the greater part of the periphery of the theater, so that it is possible to place the spectators successively facing different parts of the stage having thereon different scenes or tableaux. In this way, by placing the scenery in chronological order in successively adjacent sections of the stage, it is possible to present a series of scenes or acts without interruption or delay incident to change of scenery as is necessary in a conventional theater. Moreover, the entire absence of stage noises incident to moving scenery between scenes and acts adds greatly to the illusion and enjoyment of the play.

A panoramic scene may be made to appear to the spectators by turning the hall slowly so that they never lose sight of the performers. It is likewise possible to obtain a different panoramic effect by separating the two halves of the curtain to the extreme limit so as to permit the spectators, by turning their heads from one side of the theater to the other, to see the entire extent of the stage. In this case, also, the auditorium may be rotated slowly to facilitate the view of the spectators.

By providing a continuous uninterrupted ceiling over stage and auditorium, not only are superior acoustic effects secured but it is also possible to project upon the ceiling clouds and other images, giving the illusion of natural phenomena, such as sunrises, sunsets or similar effects.

By mounting the auditorium on a float turned by water propellers, there is secured a noiseless and vibrationless movement of the auditorium which greatly adds to the illusion of the stage moving instead of the auditorium when the latter is rotated.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. In a theater, a central floating rotatable auditorium surrounded by a stationary annular stage, a circular rotatable acoustic ceiling, a tank adapted to float the auditorium, a valve for controlling the flow of fluid to maintain the auditorium at a desired level, and means for rotating the circular ceiling.

2. In a theater, a central floating rotatable auditorium surrounded by a stationary annular stage, a rotatable acoustic ceiling positioned above the auditorium, a ceiling of parabolic configuration positioned above the stage and adapted to present a continuous

uninterrupted surface with the auditorium ceiling, a tank adapted to float the auditorium, a valve for controlling the flow of fluid to maintain the auditorium at a desired level and means for rotating the circular ceiling covering the auditorium. 70

3. In a theater, a central floating rotating auditorium surrounded by a stationary annular stage, a rotatable acoustic ceiling positioned above the auditorium, a ceiling of parabolic configuration positioned above the stage and adapted to present a continuous uninterrupted surface with the auditorium ceiling, an annular draw curtain between said auditorium and stage adapted to be rotated in unison with said auditorium and suspended by rails supported by the rotatable ceiling, a tank adapted to float the auditorium, a valve for controlling the flow of fluid to maintain the auditorium at a desired level and means to rotate the auditorium, ceiling and curtain in unison. 80

4. In a theater building, a circular rotatable auditorium, a false circular ceiling rotatably mounted above said auditorium, a draw curtain suspended from said ceiling so as to surround the auditorium, and means associated with said auditorium, and false ceiling and curtain for rotating the ceiling and curtain in unison with said auditorium. 90

5. A theater building comprising a fixed annular stage, a circular rotatable auditorium in the center of said stage, a draw curtain suspended from a ceiling of said auditorium so as to surround the same and form the walls thereof, and means associated with the auditorium and ceiling for rotating the curtain in unison with the auditorium. 100

6. In a theater, a central floating auditorium surrounded by a stationary annular stage, a false circular ceiling rotatably mounted above said auditorium, a trackway carried by said ceiling, a plurality of equally spaced rollers secured to toggle arms mounted upon said trackways, an annular draw curtain suspended from said toggle arm, said curtain adapted to surround said auditorium, means connected to said toggle arms for opening and closing said draw curtain, and other means associated with the auditorium and ceiling for rotating them together in fixed relation with respect to each other. 110

7. In a theater, a fixed annular stage, a liquid reservoir formed in the center of said stage, a plurality of baffle plates positioned around the periphery of said reservoir, a float positioned in said reservoir, an auditorium on the float, a plurality of shafts extending through said float and into the reservoir, propellers mounted upon the ends of said shafts within the reservoir, means within the float for rotating said propellers so as to cause the auditorium to rotate, a ceiling rotatably mounted above said audi- 130

torium, a draw curtain suspended from said ceiling so as to form the walls of said auditorium, and means associated with the auditorium and float and the ceiling for causing the ceiling to rotate in unison with the auditorium and float.

In testimony whereof I affix my signature.

ARTHUR J. MOULTON.
